UNITED STATES PATENT OFFICE.

EDWARD F. G. GIBBS, OF WASHINGTON, DISTRICT OF COLUMBIA.

CUTTING-OFF TOOL.

1,266,116.

Specification of Letters Patent.

Patented May 14, 1918.

Application filed November 16, 1914. Serial No. 872,442.

To all whom it may concern:

Be it known that I, EDWARD F. G. GIBBS, a citizen of the United States, residing at Washington, in the District of Columbia, 5 have invented certain new and useful Improvements in Cutting-Off Tools, of which the following is a specification.

This invention relates to new and useful improvements in cutting-off tools, such as 10 are used on common engine lathes for cutting off any such metallic substances as are held and rotated by the said lathes. I do not mean, however, to limit myself in any sense, except as required by the scope of 15 the claims.

The invention is hereinafter fully described, shown in the accompanying drawings, which form a part of this specification, and then specifically defined in the appended claims.

The object sought in this invention is to obtain the design of a cutting off tool which will be very rigid, always hold its adjustable cutting blade vertical over its lower 25 edge, adapted to either right or left hand use, provided with means for being raised or lowered to its proper elevation, and made as economically as possible.

To this end, I have designed the mechanism illustrated in the accompanying drawings, in which:—

Figure 1 is a full perspective view of the tool complete without the elevating liners referred to later.

Fig. 2 is a perspective view of the liners used for elevating the tool to its proper working position.

Fig. 3 is a central vertical sectional view of the base piece, angled clamp, cutter blade 40 and detachable king bolt head, and also a portion of the lathe's tool seat, cut on a line parallel to the axial center of the lathe and through the T-slot of its tool seat.

Reference now being had to the details 45 of the drawings by letter, similar letters refer to similar parts throughout the several views. A designates the angled base piece as a whole, while a and a² designate its horizontal and vertical wings respectively. a³ designates the edge common to both wings and a⁴, a⁵ designate the common corners. a⁵ designates the recessed shoulder, while a⁶, a⁷ point out the hard bearing spots.

55 B designates the tool seat of the lathe. C

designates the king bolt of which c is the detachable head, while c² is the nut.

D designates the horizontal adjustable cutter blade, and E is the inverted angle iron, cutter clamp, of which e and e² point 60 out the horizontal and hanging wings respectively, while e² designates the overhanging lip. F designates the clamp screw, and G the U-shaped liners.

The construction of the tool is thus de- 65 scribed:—The base piece A is known in shop practice as an "angle iron", that is a horizontal, flat, rectangular wing a, joined at one side by a very similar vertical wing a² forming an external right angled edge 70 a³ and two external corners a⁴, common to both wings.

It is held to the tool seat B, of an engine lathe, by the king bolt C, which passes through the horizontal apertured wing a, 75 the detachable bolt head c and nut c².

The upper, outer portion of the vertical wing is cut away or recessed horizontally for the purpose of forming a suitable shoulder a⁵ for the cutter blade D to rest on. 80 The said blade, which projects slightly above the top of the said vertical wing, has a hard bearing spot at each end of the said shoulder, which shoulder is cut slightly deeper between the said spots as is shown in Fig. 1. 85 This shoulder construction, in addition to giving hard bearings where they are needed, enables the cutter blade to spring downward slightly when under pressure from the angled clamp, mentioned later, and then be arrested by striking the bottom of the said deeper cut, which prevents its breaking.

The angled cutter clamp E is a small inverted angle iron, very similar in form to the base piece. In its normal position it 95 hangs entirely suspended upon the cutter blade D, which rests upon the shoulder described. With its horizontal wing e resting on the said blade, its overhanging lip e² engaging the outer edge of the said blade 100 and its hanging wing e³ supported only by side pressure against the vertical wing of the base piece, it is free to move up and down to accommodate blades of various widths, without changing its position. Its natural 105 tendency under heavy pressure from the clamp screw F, which has screw-threaded engagement with the vertical wing a², is to simultaneously spring the cutter blade down to the deeper cut referred to, while the hang- 110

ing wing e^3 presses hard against the vertical wing of the base piece and the overhanging lip draws hard against the outer edge of the blade. Thus by this arrangement, the 5 blade, caught between interlocking angle irons, is pressed from four different opposing directions by the action of the single clamp screw F , the greater pressure being up and down. The cutter blade diminishes 10 in thickness from the top edge downward for the sake of clearance.

The flat U-shaped elevating liners G , varying in thickness, are slipped under the base when necessary to elevate the cutter.

15 Rigidity, the most important feature in a cutting-off tool, is obtained by eliminating the tool post entirely and clamping the solid compact tool to the tool seat direct. It is converted from a right to a left tool simply 20 by reversing it on the tool seat and then reversing the blade.

The cutter blade cannot be easily broken by twisting or wrenching, because of its rigidity and because the spring, due to load 25 on the cutting point, is directly downward.

Having thus fully described my invention, what I claim to be new and desire to secure 30 by Letters Patent is:—

1. As an article of manufacture, a cutting- 35 off tool base piece, comprising an angle iron, the horizontal wing of which is apertured for a king bolt, while its vertical wing, adapted to screw-thread engagement with a clamp bolt, is recessed horizontally, forming 40 a shoulder on which a cutter blade is adapted to bear.

2. As an article of manufacture, a cutting- 45 off tool base piece, comprising an angle iron, the horizontal wing of which is apertured for a king bolt, while its screw-threaded vertical wing is recessed horizontally, forming a shoulder on which a cutter blade is adapted to bear, the said shoulder being cut slightly deeper between bearing spots at 50 each end.

3. A cutting-off tool comprising an angle

iron base piece, the vertical wing of which is recessed horizontally forming a shoulder on which a cutter blade is adapted to bear, a cutter blade adapted to bear on the said shoulder, a screw-pressed, inverted, angle iron cutter clamp, the horizontal wing of which is adapted to bear on the said cutter blade, while its hanging vertical wing has side pressure against the vertical wing of 55 the said base piece, and means for holding the said tool to the tool seat of an engine lathe.

4. A cutting-off tool comprising an angle iron base piece, the vertical wing of which is recessed horizontally, forming a shoulder on which a cutter blade is adapted to bear, the said shoulder having bearing spots thereon and slightly recessed between the latter at each end, a cutter blade adapted to bear 60 on the said shoulder, a screw-pressed, inverted angle iron cutter clamp, the horizontal wing of which, having an overhanging lip, is adapted to bear on the said cutter blade, while its hanging vertical wing has side 65 pressure against the vertical wing of the base piece, and means for holding the said tool to the tool seat of an engine lathe.

5. A reversible cutting-off tool comprising an angle iron base piece, the vertical 70 wing of which is recessed horizontally, forming a shoulder on which a cutter blade is adapted to bear, a cutter blade adapted to bear on the said shoulder, an inverted, interlocking, angle iron cutter clamp, the horizontal wing of which is adapted to bear on the said cutter blade, while its hanging vertical wing has side pressure against the vertical wing of the said base piece, and a king bolt which holds the said tool in reversible 75 position on the tool seat of an engine lathe.

In testimony whereof I affix my signature in presence of two witnesses.

EDWARD F. G. GIBBS.
